UNITED STATES PATENT OFFICE.

HARRY C. WALTER, OF NEW YORK, N. Y

MECHANICAL HEDGE-CLIPPER.

1,124,824.

Specification of Letters Patent. Patented Jan. 12, 1915.

Application filed December 20, 1913. Serial No. 807,830.

To all whom it may concern:

Be it known that I, HARRY C. WALTER, a citizen of the United States, and a resident of New York city, borough of Brooklyn, in the county of Kings and State of New York, have invented certain new and useful Improvements in Mechanical Hedge-Clippers, of which the following is a specification.

This invention relates to mechanical clippers, particularly of the character adapted for clipping hedges and the like.

One object of the present invention is to provide a mechanical clipper, the drive mechanism of which can be attached to the body of the operator to be actuated by one hand while the clipper is applied with the other hand to the material to be cut.

Another object is to provide a light, compact drive which may be entirely inclosed in a small casing easily carried about by the operator, and operated manually with one hand while the other hand is used for holding the clipper against the material to be cut.

The various further objects and advantages will more fully appear from the detailed description and the features of novelty consisting in the improved construction and combination of parts will be particularly pointed out in the claims.

In the drawing illustrating this invention, Figure 1 is a plan view of the improved mechanical clipper illustrating the means for attaching the gear casing to the body of the operator and the connection from the casing to the cutter blade. Fig. 2 is an elevation of the gear casing with the cover removed illustrating the interior gearing and the mode of adjustment of the handle. Fig. 3 is a section taken along line 3—3 of Fig. 2. Fig. 4 is an enlarged detail view illustrating the cutter blade and the means for reciprocating the same. Fig. 5 is a plan view partly in section taken along line 5—5 of Fig. 4. Fig. 6 is an end view of the cutter blade and its support and guide. Fig. 7 is a section taken along line 7—7 of Fig. 5, illustrating the disposition of the guide for the cross head.

Referring in detail to the drawings, the gearing for actuating the clipper is mounted in a light shell or casing 10 made preferably of aluminum or some other light metal. A freely removable cover plate 11 closes the

casing and renders the operating parts easily accessible.

The invention contemplates the attachment of the gear casing to the body of the operator, so that the gearing may be actuated by one hand while the other hand is used to hold the cutter and apply the same to the material to be operated upon. In carrying out this conception, the rear side of the casing is provided with a bendable plate 12 attached thereto at or about the midwidth thereof adjustable to the contour of the waist or trunk of the operator to which the casing is attached. The plate may be of sheet metal and suitably lined with some soft cushioning material to contact the body. Set screws 13 threaded in lugs 14 formed upon the casing may engage the plate at the corners thereof to adjust the same as may be required from time to time. The attaching means proper may consist of a strap 15 attached to an eye 16 formed on the casing, the strap passing around the waist or trunk of the operator, and if it is desired, additional straps 17 attached to eyes 18 at the top of the casing may pass over the shoulders of the operator to the opposite eyes 16 previously described or to some other convenient point. The crank handle 19 extends from one side of the casing and is shiftable in and out as hereinafter described to suit the size of waist of the operator. This handle is fastened to a shaft 20 on which is splined a gear 21 meshing with a pinion 22 upon a shaft 23. The latter has mounted thereon preferably at its opposite end a pinion 24 meshing with another pinion 25 upon a stub shaft 26 passing to the exterior of the casing and adapted to be coupled to the flexible shaft 27. Fixed on the shaft 23 at an intermediate point thereof is a bevel pinion 28 meshing with another bevel pinion 29 fixed to a fly wheel 30, rotatably mounted in the casing in a vertical plane extending laterally of the operator. By this arrangement of the fly wheel, the space within the casing is utilized with the maximum of economy and the casing is rendered very compact and of a shape convenient to be carried around about the person of the operator.

The flexible shaft above described is coupled to a bevel pinion 31 journaled in the casing 32 and meshing with a bevel gear 33 mounted in this casing. Extending from

the latter is a hand grip 34 having a hollow interior communicating with the interior of the casing 32. In this hollowed out portion of the hand grip reciprocates a slide or cross head 35 driven by a connecting rod 36 from a crank pin 37 formed upon the bevel gear 33. Connected to the cross head is a cutter bar or blade 38 formed with a plurality of teeth 39 coöperating with the stationary teeth 40 formed upon a bar 41 extending from the hand grip. The cutter blade may be guided and held to the bar 41 by yokes 42 having teeth 43 engaging recesses formed in the bar 41 and provided with guide screws 44 extending over a shoulder 45 formed upon the blade 38, and loosely engaging the latter so that the same may reciprocate within the yokes. Thus, when it is desired to remove the blade, it is merely necessary to unscrew the screws 44 and detach the blade from the cross head 35 which may also be accomplished through a screw connection. The guide way 46 for the slide 35 may conveniently consist of journals formed at the line of separation of the two halves of the hollow hand grip, thus facilitating the ease and promoting the cheapness of construction.

For adjusting the handle toward and from the casing to suit the size of the waist of the operator, the end of the shaft 20 is grooved and braced by a fork 46 which is clamped to the interior of the casing by a screw 47 extending inward from the exterior of the casing through a slot 48. The screw may be loosened and moved along the slot, thus carrying with it the fork and thus actuating the shaft and handle to adjust the same in the desired position relatively to the casing.

It will thus be seen that I have provided an improved mechanical hedge clipper which may be carried about the person of the operator and driven with one hand while the other hand is used for applying the cutter to the hedge. The various parts are so arranged and constructed as to promote the convenience of the operator and facilitate the ease of the operation with a device which is light, compact and efficient.

Having thus described my invention, I claim as new and desire to secure by Letters Patent:

1. In a device of the character described, 55 gear casing, means for attaching the same to the body of the operator, a handle extending from the casing whereby the gearing is actuated by one hand of the operator and a driven shaft extending from the casing, a cutter actuated thereby, and a hand grip disposed between the shaft and cutter whereby the cutter may be held by the other hand of the operator and applied to the material to be cut, the mechanism directly actuating the cutter being concealed within

the hand grip, and the latter being in longitudinal alinement with the cutter.

2. A portable mechanical hedge clipper comprising a light gear casing, means for attaching the casing to the body of the operator, gearing within the casing, a handle extending from one side of the casing and operated by one hand of the operator for actuating the gearing, a flexible shaft driven by the gearing and extending from the opposite side of the casing, a cutter reciprocated by the flexible shaft, and a hand grip for the cutter disposed in longitudinal alinement therewith, between the cutter and flexible shaft which hand grip the operator may grip with his other hand to apply the cutter to the material to be cut, the mechanism directly actuating the cutter being concealed within the hand grip.

3. A mechanical clipper comprising a gear casing, an adjustable plate attached to one side thereof and adapted to be adjusted to the contour of the waist of the operator, means for fastening the gear casing to the waist of the operator, a handle extending from the casing operated by one hand of the operator for driving the gearing, a cutter driven by the gearing, and a hand grip integral with the cutter and adapted to be grasped adjacent thereto whereby the cutter may be applied to the material to be cut with the other hand of the operator, all moving parts except the cutter and operating handle being concealed by the casing and hand grip.

4. A mechanical clipper comprising a gear casing, an adjustable plate attached to one side thereof and adapted to be adjusted to the contour of the waist of the operator, means for adjusting and holding the plate in the proper position of adjustment, means for fastening the gear casing to the waist of the operator, a handle extending from one side of the casing operated by one hand of the operator for driving the gearing, a cutter driven by the gearing, and a hand grip extending from the opposite side of the casing whereby the cutter may be applied to the material to be cut with the other hand of the operator, said grip being in longitudinal alinement with said cutter, all moving parts except the cutter and operating handle being concealed by the casing and hand grip.

5. In a mechanical clipper, a casing, gearing provided therein, means for attaching the casing to the waist of the operator, a handle operatively connected to the gearing extending to the exterior of the casing and adjustable toward and from the casing to suit the size of the waist of the operator, said handle being operated by one hand of the operator, a flexible shaft extending to the exterior of the casing and driven from the gearing, a cutter reciprocated by the

shaft, and a hand grip for the cutter adapted to be held by the other hand of the operator while the gearing is being actuated by the latter to reciprocate the cutter, all moving parts except the cutter and operating handle being concealed by the casing and hand grip, said hand grip connecting the cutter with the shaft and disposed in longitudinal alignment therewith.

6. In a mechanical clipper, a casing, gearing provided therein, means for attaching the casing to the waist of the operator, a handle operatively connected to the gearing extending to the exterior of the casing and adjustable toward and from the casing to suit the size of the waist of the operator, adjusting means extending to the ex-

terior of the casing for positioning the handle, said handle being operated by one hand of the operator, a flexible shaft extending to 20 the exterior of the casing and driven from the gearing, a cutter reciprocated by the shaft, and a hand grip for the cutter adapted to be held by the other hand of the operator while the gearing is being actuated by 25 the latter to reciprocate the cutter.

Signed at New York city, in the county of New York, and State of New York, this 15th day of December A. D. 1913.

HARRY C. WALTER.
